Specification for Design.

Patented June 21, 1910.

Application filed October 30, 1909. Serial No. 525,599. Term of patent 14 years.

To all whom it may concern:

Be it known that I, ALANSON F. DIETZ, a citizen of the United States, residing at Altamont, in the county of Albany and State of New York, have invented a new, original, and ornamental Design for Checkrein-Holders, of which the following is a specification, reference being had to the accompanying drawing, forming part thereof.

In the drawings, Figure 1 is a perspective

view of a check-rein holder, showing my new design. Fig. 2 is a side elevation of the same.

I claim:

The ornamental design for a check-rein holder, as shown.
